United States Patent Office

Des. 182,702

Patented May 6, 1958

182,702

SIDE HANDLES FOR TRAYS OR THE LIKE

Ralph B. Billig, Westlake, and Manuel S. Ziskin, Mayfield Heights, Ohio, assignors to Kromex Corporation, Cleveland, Ohio, a corporation of Ohio

Application August 15, 1957, Serial No. 47,375

Term of patent 14 years

(Cl. D44—10)

FIG.2

Fig. 1 is a top plan view of a pair of side handles for trays or the like showing our new design; and
Fig. 2 is an elevation view thereof.

We claim:

The ornamental design for side handles for trays or the like, as shown and described.
